E. J. KINGWILL

SASH AND DOOR LOCK

Filed July 25, 1924

UNITED STATES PATENT OFFICE.

EDWARD J. KINGWILL, OF SANTA MONICA, CALIFORNIA, ASSIGNOR OF ONE-HALF TO
CHARLES G. KINGWILL, OF HAMMOND, INDIANA.

SASH AND DOOR LOCK.

Application filed July 25, 1924. Serial No. 728,123.

To all whom it may concern:

Be it known that I, EDWARD J. KINGWILL, a citizen of the United States, residing at Santa Monica, in the county of Los Angeles 5 and State of California, have invented new and useful Improvements in Sash and Door Locks, of which the following is a specification.

This invention relates to improvements in 10 sash or door locks.

It is an object of the invention to provide a cheap, simple and durable device adapted to be mounted upon one of a pair of sliding window sashes or upon a door which will 15 frictionally hold the sash or door upon which it is mounted, in a desired position.

It is another object of the invention to provide a device adapted to be mounted upon one of a pair of sliding window sashes 20 such that said window sashes may be held in open position but cannot be opened further from the outside thereof.

It is a further object of the invention to provide a device adapted to be mounted upon a door and which will frictionally hold the door in partly open position, but which will prevent further opening movement thereof.

With the foregoing and other objects in 30 view which will be made manifest in the following detailed description and specifically pointed out in the appended claims, reference is had to the accompanying drawing for an illustrated embodiment of the preferred form of the invention, wherein:

Fig. 1, is a partial perspective view of a pair of sliding window sashes, upon which the improved locking device is mounted.

Fig. 2, is a vertical section taken through 40 the window sashes, shown in Fig. 1.

Fig. 3, is a top plan view of the improved sash and door lock.

Fig. 4, is a vertical section, taken substantially on the line 4—4 of Fig. 3.

Fig. 5, is a vertical section taken through 45 the device as applied upon a door.

Referring to the accompanying drawing wherein similar reference characters refer to similar parts, the improved device consists of a base member, having a bottom part 50 10, and upstanding sides 11 and 12, preferably formed integral therewith. A pair of bosses 13 and 14, are provided upon opposite sides of the base 10, to provide a pair of openings or apertures 15 and 16, to receive

screws 17, for mounting the device. Upon the back of the base plate 10, is formed an upstanding shoulder 18, in which is formed a groove 19, for a purpose hereinafter to be more fully described.

A pintle 20, herein shown as being in the form of a bolt is screwed into the base plate 10, by means of threads 21. On the pintle 20, is slidably mounted an engaging member 22, having an enlarged head 23, and a coil spring 24, coiling about the pintle 20.

The engaging member is provided with an elongated slot 25, to permit up and down sliding movement of the engaging member 22, upon the pintle 20, or forward and backward movement upon such pintle. Upon the underside of the engaging member 22, is formed a groove 26, adapted to receive the extension 27, of the coil spring 24, so that the coil spring 24, serves to urge the engaging member 22, into uppermost position and to urge the engaging member toward the rear side 18.

A handle 28, is also pivoted upon the pintle 20, above the engaging member 22, and is provided with a depending portion 29, movable within a groove 19, and which engages a cam face 30, on the rear of the engaging member 22. When the handle 28, is in the position shown in Fig. 3, the engaging member 22, assumes the position 55 substantially as that shown in Fig. 4, that is, with the spring 24, urging the engaging member against the handle 28, and rearwardly and into its rearmost position against the depending portion 29, of the handle 28.

Upon the handle 28, being swung as indicated by the arrow A in Fig. 3, the engagement of the depending portion 29, upon the cam face 30, will cause the engaging member 22, to be shifted forward upon 60 the pintle 20, against the action of the extension 27, of the coil spring 24. This brings the enlarged head 23, of the engaging member, which is provided with a rubber covering 32, into engagement with the stile of the sash S, as the device is mounted upon the lowermost sash S' shown in Figures 1 and 2.

Because of the shape of the head 23, which is similar to a parallelogram in cross section, the sash S' upon which the device 65 is mounted, may be brought downwardly from the position shown in Fig. 2, or into closed position. This may be done by overcoming the friction of the engagement of the rubber cover 32, against the sash S, as 70

75 80 85 90 95 100 105 110

Because of the shape of the head 23, which is similar to a parallelogram in cross section, the sash S' upon which the device 65 is mounted, may be brought downwardly from the position shown in Fig. 2, or into closed position. This may be done by overcoming the friction of the engagement of the rubber cover 32, against the sash S, as 70

clearly shown in Fig. 5, where the device is illustrated as being mounted upon a door D. Upon the door being forced in the direction indicated, the rubber cover 32, engages upon the floor F causing the enlarged head 23, to wedge against the floor. That is, the engaging member 22, slides upon the pintle 20, and moves about the cam face 30, as a center toward the door D, thereby compressing the spring 24. This movement tends to urge the head 23, into a tighter or firmer engagement with the floor F, and such engagement will constantly increase as long as the door is attempted to be forced open. The same action occurs between the device and the window sash S, when the lock is mounted upon a window.

From the above it will be seen that an improved sash or door lock is provided which will frictionally engage a surface and which will permit movement of such surface with respect to the lock in one direction, providing the friction of engagement is overcome and which will positively prevent movement of such surface in the opposite direction with respect to the lock.

It is to be understood that various changes in the details of construction may be made without departing from the spirit or scope of the invention as defined by the appended claims.

What I claim is:

1. A sash and door lock including a pintle, an engaging member having a slot therein, through which said pintle extends, spring means for urging said member to assume an upwardly inclined position upon said pintle, and means for causing said member to slide forwardly so as to cause its engaging end to engage a surface, whereby movement of said surface relatively to said lock will cause said engaging member to pivot about its opposite end and wedge against said surface.

2. A sash or door lock, comprising a base member, a pintle secured upon said base member, a handle pivotally mounted upon the free end of said pintle, an engaging member slidably upon said pintle, a spring disposed beneath said engaging member and urging it into uppermost and rearmost position with respect to said base member, a projection founded upon said handle and adapted to engage a cam face upon said engaging member whereby movement of said handle will produce forward movement of said engaging member.

3. A sash and door lock including an engaging member slidable between a pair of

side members, spring means for causing said engaging member to assume an inclined position between said side members, and means for causing said engaging member to slide forwardly between said side members so as to cause its engaging end to engage a surface, whereby movement of said surface relatively to said lock will cause said engaging member to swing about its opposite end and wedge against said engaging surface.

4. A sash and door lock comprising a pintle, an engaging member having a slot therethrough, through which said pintle extends, means for preventing rotation of said engaging member upon said pintle, spring means disposed about said pintle adapted to urge said engaging member into an inclined position, and a handle pivoted upon said pintle adapted upon swinging movement to force said engaging member forwardly in an inclined position, so that the engaging end of said engaging member may engage upon a surface, whereby movement of said surface relatively to said lock will cause said engaging member to pivot upon its end opposite the engaging end and wedge against said surface.

5. A sash and door lock comprising a base member having upstanding sides, a pintle upon the base member between the sides, a slotted engaging member positioned between said sides with the pintle extending through the slot therein, a handle pivoted upon said pintle, there being a cam surface upon said engaging member engageable by a portion of the handle, whereby upon movement of the handle, the engaging member may be moved into engaging position, and spring means for urging said engaging member into disengaged position.

6. A sash and door lock comprising a base member having upstanding sides, a pintle upon the base member between the sides, a slotted engaging member positioned between said sides with the pintle extending through the slot therein, a handle pivoted upon said pintle, there being a cam surface upon said engaging member engageable by a portion of the handle, whereby upon movement of the handle, the engaging member may be moved into engaging position, and a spring disposed about said pintle between said engaging member and base member urging the engaging member into uppermost and disengaged positions.

In testimony whereof I have signed my name to this specification:

EDWARD J. KINGWILL.
